UNITED STATES PATENT OFFICE.

ALFRED FAULKNER, OF JERSEY CITY, NEW JERSEY, ASSIGNOR TO ELI W. BROADBENT, OF NEW YORK, N. Y.

DESIGN FOR A SEWING-MACHINE FRAME.

SPECIFICATION forming part of Design No. 18,982, dated April 2, 1889.

Application filed January 12, 1889. Serial No. 295,990. Term of patent 14 years.

To all whom it may concern:

Be it known that I, ALFRED FAULKNER, of Jersey City, in the county of Hudson and State of New Jersey, have invented and produced a new and original Design for a Sewing-Machine Frame, of which the following is a specification.

I will describe my design in detail, and then point out the novel features in a claim.

10 The accompanying drawing is a side elevation of a sewing-machine frame embodying my design.

15 My design consists, essentially, of a single vertically-extending portion, A, and two horizontally-extending portions, B C, one above the other, the whole being arranged above a base portion, D. The vertically-extending portion A has approximately-parallel side edges for a distance. The outer edge of the 20 vertical portion is curved inwardly, as at a, and then again extends vertically, as at a'. Above the vertically-extending portion a' is a sinuously-curved portion, a². Above the sinuously-curved portion a² is a horizontally-extending portion, a³. Beyond the horizontally-extending portion a³ is a horizontally-extending but ogee-curved portion, a⁴. Beyond the ogee-curved portion a⁴ is a horizontally-extending portion, a⁵. The inner edge 25 of the vertically-extending portion A is surmounted by a general horizontally-extending curved portion, a⁶. From the horizontally-extending curved portion a⁶ is a downwardly-extending vertical portion, a⁷. From the 30 downwardly-extending portion a⁷ extends an ogee-shaped portion, a⁸. Below the portion a⁸ is a horizontally-extending portion, a⁹. Between the portions a⁴ a⁵ and the portions a⁷ a⁸ is a portion, E, comprising an upper horizontally-extending portion, e, a downwardly-extending curved portion, e', a vertically-extending straight portion, e², a horizontally-extending straight portion, e³, and a downwardly-extending ogee-shaped portion, e⁴. 35 The lower portion, C, upon its outer edge comprises a vertically-extending portion, c, and a general horizontally-extending curved portion, c', and a vertically-extending straight portion, c². The upper edge, c⁵, of the portion C is approximately curved in a horizontal direction and parallel with the edge portion c'. From the portion c⁵ is a vertically-extending portion, c⁶. Beyond the portion c⁶

is a horizontally-extending straight portion, c⁷. Between the portions c⁶ c⁷ is a curved portion, c⁸. From the portion c⁷ is a vertically-extending portion, c⁹. Extending from the portion c⁹ is a horizontally-extending portion, c¹⁰. The base portion D comprises upon one side an angularly-extending portion, d, 55 and upon its other side an angularly-extending portion, d'. From the portions d d' extend downwardly and outwardly curved portions d² d³. Below the portions d² d³ is a portion, d⁴, having approximately-parallel top 60 and bottom sides and approximately-parallel ends. The general outline of all the parts of this frame is round.

What I claim as my design is—

The design for a sewing-machine frame 70 herein shown and described, consisting of a vertically-extending portion, A, having approximately-parallel sides, and an outer edge having the inwardly-curved portion a and the straight portion a'; the portion B, having 75 upon its upper edge the sinuously-curved portion a², the horizontally-extending portion a³, the ogee-curved portion a⁴, and the horizontally-extending portion a⁵, and upon its lower edge the horizontally-extending 80 curved portion a⁶, the downwardly-extending portion a⁷, and the ogee-shaped portion a⁸, the horizontally-extending portion a⁹; the intermediate portion, E, comprising the horizontally-extending portion e, the downwardly-extending curved portion e', the straight portion e², the horizontal portion e³, and the ogee-shaped portion e⁴; the portion C, comprising upon its outer edge the vertically-extending portion c, the horizontally-extending curved portion c', and the vertically-extending straight portion c², and comprising 85 upon its inner edge the curved portion c⁵, the vertically-extending portion c⁶, the horizontally-extending straight portion c⁷, the vertically-extending portion c⁸, and the horizontally-extending portion c¹⁰, and the portion D, comprising the angularly-extending portions d d', the downwardly and outwardly curved portions d² d³, and the portion 90 d⁴, as set forth.

ALFRED FAULKNER.
